ATTORNEY

UNITED STATES PATENT OFFICE

LEON J. MORIN, OF TAUNTON, MASSACHUSETTS

AUTOMOBILE CURTAIN CONTROL

Application filed February 27, 1930. Serial No. 431,661.

My invention relates to a manually operated device for operating a curtain from a distance particularly a rear curtain in an automobile. The annoyance caused by glaring headlights shining through the rear window of an automobile is well recognized by the average operator who unless accompanied may be forced to stop to lower the rear curtain with the consequence that a little later he 10 may desire the same curtain raised and perforce must stop again.

It is an object of my invention to provide a manually operated remote control device for raising or lowering a curtain which is 15 simple in structure and reliable in operation.

A further object of my invention is to provide a manually operated remote control device for operating a rear automobile curtain wherein the curtain is suitably weighted 20 so that it descends by reason of said weight and is raised by a tape or strand operated by a handle near the driver with a suitable means for holding said curtain in a raised position 25 and means for limiting the travel in either direction.

Other objects and advantages will appear from the detailed description which follows taken in connection with the accompanying 30 drawings.

I attain these objects and advantages by means of mechanism illustrated in the accompanying drawings wherein:—

Figure 1 is a sectional side elevation of 35 parts of a closed automobile, illustrating the general relation of the several parts of my invention.

Figure 2 is an elevational view showing the 40 curtain with its rod weight, portions of the curtain being cut away to show the window, the tape wound end of the curtain roller and the rod weight.

Figure 3 is an enlarged elevational view of 45 the fixture containing the handle for operating the curtain with stop means for limiting the movement of the curtain in either direction.

Figure 4 is an elevational view of the front 50 half of the fixture showing the position of

the handle when the curtain is completely raised.

Figure 5 is a cross sectional view taken along the section line shown in Figure 3 looking in the direction of the arrows showing parts in full. 55

Figure 6 is a plan view of a modified form of curtain raiser the ring contacting the guide when the curtain is down and engaged by the hook when the curtain is raised. 60

Similar numerals refer to similar parts throughout the several views.

In the drawings, the curtain roller 1 is provided with a reduced end portion 2 at one end thereof and is mounted on a one piece bracket 3 as shown in Figures 1 and 2. One end of the curtain roller is provided with a pintle 4 to fit into a hole provided therefor in the bracket the other end which may be called the tape holding end is provided with a disc member 5, having a central opening for the reception of the screw passing through the hole in the bracket 3 to support the same for rotary movement. 65

As stated before the reduced end of the 70 roller is of a diameter substantially two-thirds the diameter of the roller and is of a width equal to that of the tape or strand which is used to turn the roller. The tape 6 is wound around the reduced end and is 75 threaded through a guide 7 which may or may not be provided with a sheave to facilitate the traveling of the tape, whence it passes through another guide 8 secured to the body B of the automobile to the actuating device 80 85 which will be described.

The curtain shade 9 is secured in the usual manner to the roller and the lower or free end of the curtain shade is provided with a rod or bar 10 of some heavy material, preferably 90 metal, sufficient in weight to lower the curtain when released, by force of gravity alone. The ends of the rod 10 are holed to receive the guide strings 11, 11 secured to the bracket 3 and the eye hooks 12. The window 13 represents the usual type to be found in the rear of automobiles. A tassel 14 may be attached to the tape 6 as shown in Figure 1 to enable anyone seated in the back seat to raise the curtain temporarily. It is to be understood 95 100

that the showing in Figure 1 is representative of the manner of use and the tape may be exposed or concealed within the upholstery as desire dictates.

5 The mechanism for raising the curtain is shown in Figures 3 to 5 inclusive. The end of the tape 6 is secured to the screw 15 within the fixture 14 and passes around the sheave 16 operated by the handle 19. As shown 10 more fully in Figure 5 the sheave is secured by the bolt 17 to the slide 18 having the handle 19. The fixture 14 has a portion 20 stamped out whereby it may be secured by screws to the top of the automobile. The 15 slide 14 with its sheave 16 is freely slideable within the slot 21 in the fixture and is shown in locked position in Figure 4. An adjustable stop member 22 may be used to secure adjustment if necessary to limit the downward movement of the curtain.

20 It will be seen that with the mechanism described the curtain travels twice as far as the slide, since the tape is doubled, therefore the slide should be arranged to travel a distance 25 equal to one half the travel of the curtain.

25 In the modification shown in Figure 6 a much simpler means of raising the curtain is disclosed consisting of the tape 6, a guide 23, a ring 24 and hook 25. When the curtain is lowered the ring 24 is snugly contacting the guide 23 and when pulled out and hooked as shown the curtain is in the raised position. The distance between the guide 23 and the hook 25 should be substantially equal to the 35 distance the curtain shade travels. Of course the ring as well as the other raising mechanism should be so located as to position to be conveniently accessible to the operator.

40 The mode of operation is apparent from an inspection of the drawings. As previously stated the termini of travel of the handle or ring means must correspond to the travel of the curtain. When either the handle or the 45 ring is released the curtain descends by reason of the rod weight provided therefor and when it is desired to raise the curtain the handle or ring is pulled and locked, in the case of the handle by a right angle turn on the fixture and in the case of the ring by engagement with the hook.

50 I desire it to be understood that other approved means operating the tape may be used such as a rack and a handle with teeth to engage the rack or a different form of ring without departing from the spirit of my invention.

55 All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any

variations in structure or substitution of equivalents which utilize the principle of my invention and fall within the purview of my invention and are within the spirit and scope 70 of the following claims:

The invention having been set forth what is claimed as new and useful is:

1. In combination with a shade roller for an automobile window, said shade roller being freely rotatable and unrestrained, of 75 gravity means for lowering the curtain, of a flexible member adapted to be wound upon a portion of said roll when the curtain is lowered, means to lock the free end of said flexible member to restrain the lowering of 80 said curtain, said locking means comprising a pivotal slide, means for guiding said slide including a transverse portion, serving as a stop for said slide and adapted to be engaged by said slide by a pivotal movement 85 thereof.

2. In an automobile curtain of the roller type, a flexible member or tape for controlling the rolling and unrolling of said curtain, said flexible member or tape having one 90 end thereof wound upon the roller, the other end being anchored, and means for varying the length of the flexible member or tape by a fractional movement of the curtain.

3. In a remote control for a curtain, a 95 flexible member or tape for rolling or unrolling said curtain, means for locking the free end of said flexible member or tape, a slide engaging an intermediate portion of said member, whereby the curtain may be moved 100 by a fractional movement of said slide.

4. In a remote control for a curtain, a flexible member or tape for rolling or unrolling said curtain, means for locking the free end of said flexible member or tape, a 105 slide engaging an intermediate portion of said member, whereby the curtain may be moved by a fractional movement of said slide, and means to lock said slide in the raised position of said curtain.

5. In a remote control for a curtain for automobiles, said curtain being mounted upon a roller, including a flexible member or tape, having one end thereof wound upon a portion of said roller, the opposite end being in proximity for operation by the driver of said automobile, a bracket to which said end is connected, said bracket including a slide, said slide engaging said flexible member or tape to roll or unroll said curtain, said slide including a portion thereof formed to anchor said flexible member or tape by engagement with said bracket.

6. A remote control for a roller curtain of 125 an automobile, adapted to be operated by a flexible member or tape, locking mechanism adjacent a remote point of said automobile, said locking mechanism including a bracket adapted to engage and anchor said flexible 130

member or tape, and comprising a slide engaging said flexible member or tape, a slot in said bracket in which said slide is guided, said slide being pivotally mounted within said slot, and an abutting portion formed on said bracket, forming means to anchor said slide by a pivotal movement thereof.

7. In a roller curtain for automobiles, or the like, a remote control therefor, comprising a flexible member or tape serving to actuate said curtain into the rolled or unrolled position, locking means for said flexible member or tape adapted to be positioned at the remote control point, said locking means comprising a bracket, a guide formed on said bracket, a slide pivotally mounted upon said guide, and an abutting wall formed on said bracket adapted to be engaged by said slide, by a pivotal movement 20 of said slide, to hold said curtain in one extreme position thereof.

8. In a remote control for a roller curtain of an automobile, and including a flexible member or tape for rolling or unrolling said curtain, locking mechanism for said flexible member or tape, comprising a bracket, a guide formed on said bracket, a portion thereof being formed with an abutting wall at one end thereof, a slide engaging said flexible member or tape to operate the same for rolling or unrolling said curtain, said slide being pivotally connected with said guide of said bracket, whereby it may be moved into position engaging said abutting 35 wall.

9. In a remote control for a roller curtain of an automobile, and including a flexible member or tape for rolling or unrolling said curtain, locking mechanism for said flexible member or tape, comprising a bracket, a guide formed on said bracket, a portion thereof being formed with an abutting wall at one end thereof, a slide engaging said flexible member or tape to operate the same for 40 rolling or unrolling said curtain, said slide being pivotally connected with said guide of said bracket, whereby it may be moved into position engaging said abutting wall, and an adjustable stop at the other end of 45 said guide.

Signed at Providence, in the county of Providence, State of Rhode Island, this 14th day of February, 1930.

LEON J. MORIN.
